[57] CLAIM

The ornamental design for curved kabob holder, as shown and described.

DESCRIPTION

FIG. 1 is a view in perspective of a curved kabob holder embodying our new design;

FIG. 2 is a top plan view thereof; the bottom plan view is a mirror image thereof;

FIG. 3 is a front elevational view thereof; the right side view is identical thereto;

FIG. 4 is a left side elevational view thereof; and,

FIG. 5 is an inverted rear elevational view thereof.
